UNITED STATES PATENT OFFICE.

LUCIEN A. BROTT, OF BROOKLYN, NEW YORK, ASSIGNOR TO THE COMPOSITE TYPE BAR COMPANY, OF JERSEY CITY, NEW JERSEY, A CORPORATION OF NEW JERSEY.

TYPE-MAGAZINE.

SPECIFICATION forming part of Letters Patent No. 694,310, dated February 25, 1902.

Application filed July 16, 1900. Serial No. 23,819. (No model.)

To all whom it may concern:

Be it known that I, LUCIEN A. BROTT, a citizen of the United States, residing at Brooklyn, in the county of Kings and State of New York, have invented certain new and useful Improvements in Type-Magazines; and I do hereby declare the following to be a full, clear, and exact description of the invention, such as will enable others skilled in the art to 50 which it appertains to make and use the same.

My invention relates to a type-magazine for typographic machines. Its object is to provide a magazine which shall receive type elements, and especially wedge-shaped justifiers, and feed them gradually or in succession 15 and butt-end forward toward the discharge end of the magazine.

In preceding applications—for example, in my application filed March 10, 1900, on which 20 patent will be granted of even date with this—I have described a machine comprising means for casting types and storing them in assorted columns, composing a line, transferring the line, and finally transforming the line into a 25 type-bar—briefly, the combination in an organized machine of type-setting and bar-forming means to produce a type-bar.

During the composition of the line I introduce small wedge-shaped justifiers, which are 30 placed to lie at right angles to the substantially vertical character-bearing and other types, the apex of a justifier lying between the shoulders of two types just below their faces. The assembled line is transferred to 35 a “bar-block” hung upon the end of an arm journaled upon the side of the machine. The bar-block swings up to a mouth of the melting-pot, the justifiers being forced in to justify the line during the upward movement. 40 At the pot molten metal is cast into the spaces below the justifiers, and the line is converted into a type-bar. On the return movement of the bar-block the justifiers are knocked out of the type-bar, and the magazine, which is 45 the subject of this application, is provided to receive them and supply the needs of composition.

This magazine comprises, essentially, a receptacle having a substantially vertical chan-

55 bottom leading to a chute, (not shown,) a movable partition or false bottom, means for opening the partition gradually from one end to the other, and mechanism for regulating the action of the means for moving the partition.

In the accompanying drawings, Figure 1 is an elevation of the machine, showing the magazine in place. Fig. 2 is an end elevation of the magazine. Fig. 3 is a rear view. 60 Fig. 4 is a horizontal section on line 4-4, Fig. 3. Fig. 5 is a plan. Fig. 6 is a vertical section on line 6-6, Fig. 3. Fig. 7 is a view of a portion of the operating-slide. Fig. 8 is a detail of the rack, illustrating the manner of 65 operating the partition of the magazine; and Fig. 9 illustrates the manner of suspending the partition of the magazine. Fig. 10 is a detail to accompany Fig. 7.

In Fig. 1 I have illustrated the side of the 70 machine which carries the justifier-magazine. In that figure I have used the reference-letters which designate corresponding parts in the preceding application before named, the magazine itself being generally designated 75 by the letter S. Its parts, as shown on Sheet 2, are designated by numerals.

I will briefly describe some of the elements of the machine as shown in Fig. 1. A is the power-shaft, A³ is the frame of the machine, 80 and A⁶ the cap. C is the melting-pot. F¹ is one of a pair of slides carrying the mold operator and selector governing the discharge of cast types, and f³ is a pinion which operates the slide. P¹ is the crank and P² the connecting-rod, and P³, which they actuate, is the arm which carries the bar-block. P⁴ is the rear operating-arm to exert a downward pull on the arm P³ just before its return movement after it has swung up the bar-block. 90 P⁵ is the arm which engages the rack-bar P⁶, the rack-bar operating to revolve the bar-block. P⁷ is the divided cam-plate, which governs the action of the rack-bar. P¹⁷ is the rock-shaft, and P¹⁸ the arm carried by the rock-shaft, which actuates the arm P⁵. P²² is the arm carrying the lower division of the cam-plate P⁷, so that the cam-plate may open and form two different cam-paths to govern the 95 operation of the rack-bar P⁶, either to draw 100

it in or to throw it out, according to the path taken by the roller on the end of the arm P^8 . R' is the bar-block, which carries the assembled line of types and which is swung on the 5 end of the arm P^8 . R^{10} is a mutilated gear on the bar-block through which the rack-bar P^6 partially rotates the bar-block in one direction as the bar-block is swung up and in the opposite or return direction as it is 10 brought back. Q is a pump, and Q^2 is the mouth of the melting-pot, to which the bar-block is presented. R^{12} is a slide carrying tappets and camways for operating elements of the bar-block, justifier-magazine, and bar-galley. r^{105} is the lever which actuates the slide R^{12} . S is the justifier-magazine. T' is the box of the bar-galley; T^2 , the stick or holder for the type-bars; T^3 , the packer for the bar-galley, and t^9 the arm which operates the 15 packer T^3 .

Power applied through the shaft A sweeps the crank P' around to the right, the connecting-rod P^2 drawing down the end of the lever-arm P^8 and starting the bar-block R' on its 20 way to the mouth Q^2 of the melting-pot C . The rock-shaft p^{17} turns, carrying back the arm P^5 and pulling back the rack-bar P^6 , which engages the mutilated gear R^{10} and partially rotates the bar-block. The types are now 25 lying in a channel in the bar-block, their heads down with the thin ends or apexes of the justifiers across the line, each between the shoulders and near the heads of two types. The bar-block is brought up to the mouth Q^2 of 30 the melting-pot and dwells there till the metal is cast into the spaces between the type and beneath the justifiers, whereupon the bar-block after a slight downward movement through the pull of the arm P^4 on the arm P^3 35 is started upon its return movement. One of the first operations on this return movement is to knock out the justifiers, which fall into the mouth of the magazine, the type-bars being subsequently discharged upon the stick or holder T^2 of the bar-galley box T' , the bar-block then swinging back to its original position.

Referring now to the views of Sheet 2, Figs. 2 to 9, illustrating the improved justifier-magazine, 1 represents a front plate, 2 a rear plate, and 3 a channel with an inclined bottom 4. The channel 3 comprises three divisions, an upper 5, a lower 6, these two being vertical and in different planes, and an intermediate inclined division 7, connecting 5 and 6 and having a shoulder 8. Between the divisions 6 and 7 of the channel lies a movable partition or false bottom 9, supported at each end by pivoted swinging hangers 10. The 55 partition is of trapezoidal form, the front being inclined, so that the width of the bottom gradually increases from one end to the other. At one end is a pin or projection 11. The rear plate 2 has at each end a bracket extension 12. The one adjacent the machine is grooved to receive a rack 13 and a trip-arm 14, L-shaped in cross-section, pivoted to the

rack and pressed by a spring 15, so that its top normally lies against a wall of the groove and away from the rack. A shaft 16 is journaled in the bracket extensions 12 and bears at the machine end a pinion 17, which meshes with the rack 13. One end of the shaft is encircled by a drawn spring 18, one arm of which bears against a hanger 10, the other end engaging a pin 19, which is held by and projects from an arm 20, fixed to the shaft 16. A spring-pressed pawl 21 is mounted on the arm 20 and engages a ratchet 22, which is mounted on a sleeve 23, loose on the shaft 16. The opposite end of the sleeve is provided with a gear-wheel 24, which, with a gear-wheel 25, constitutes a bevel-gear. The gear-wheel 25 carries an escapement-wheel 26, and both are mounted on a stud 27, secured to a block or projection 28, the block being recessed, as indicated at 29, to permit the movement of the movable bottom 9. The escapement-wheel with a detent or anchor 30, fork 31, and counterbalance 32 constitute the familiar escapement and pendulum or clock mechanism. In a recess in the upper part of the magazine in the front plate 1 lies a serrated slide 33, which is held by a spring 34 in the path of an incline 35 on the slide R^{12} . It is the function 95 of the serrations to receive and guide the tops or apexes of the justifiers and tilt them just before their discharge from the upper channel of the magazine. The arm t^9 is pivoted to one end of the front plate 1, its free end playing in a recess-guide at the other end of the plate. This arm is reciprocated by the action of the slide R^{12} and operates the packer-arm T^3 to force down the type-bars and holder lying in the galley, as described in my designated application.

Operation: The line of type having been transformed into a type-bar at the mouth Q^2 of the melting-pot and the bar-block having begun its return to its original position, the slide R^{12} is depressed by means of the bell-crank lever r^{105} , as described in my designated preceding application, causing the discharge of the justifiers. The justifiers fall into the mouth of the magazine S , their butt-ends striking the shoulder 8, so that each justifier is tilted forward to insure placing the apex of each one in one of the openings or between two of the teeth of the serrated slide 33. A projection 36 on the face of the slide R^{12} now engages the top of the rack 13 and depresses it, thereby turning the pinion 17 and its shaft 16, throwing over the arm 20, and through the pin 19 tensioning the spring 18, so that it is stored with energy. As the rack 13 descends the arm 14 travels with it, the top of the arm sliding down a wall of its channel, yielding to pass the pin or projection 11, and then snapping under the pin, so that the beveled shorter side of the L may take in behind the pin on the upward movement of the rack and arm. The slide R^{12} is now carried up, removing pressure from the rack 13, which is free to be lifted to its first

position by the action of the pinion 17, driven by the spring 18. As the rack rises the beveled side of the arm 14 forces out the pin 11 and opens the movable bottom. The escape-
 5 ment regulates the action of the trip-arm on the pin, so that the partition is gradually and gently opened to offer a discharge-opening which widens from end to end, so that the justifiers are discharged in even succession,
 10 each one reaching the mouth of the supply-chute without interference. It is necessary to the proper working of this device that the justifiers should strike the inclined bottom 4 so that they shall be discharged butt-end first. To accomplish this positioning is the
 15 function of the serrated slide 33. An incline 35 on the slide R¹² as the slide starts up engages the end of slide 33 and forces it over, tilting the justifiers into a line approaching
 20 the inclination of bottom 4. When a justifier falls, it strikes the bottom 4 in such a manner that it invariably slides to the discharge-point butt-end first. At the end of the move-
 25 ment the spring 34 holds the slide 33 in en- gagement with the face of slide R¹², but below the incline 35, so that the slide 33 is ready on the downward movement of slide R¹² to move into engagement with the in-
 30 cline 35. The movable bottom of the maga- zine at the same time is free to be returned to its normal position under pressure of the end of spring 18, which presses against one of the hangers 10, the arm 14 having passed beyond pin 11.
 35 As indicated in the statement of invention hereinbefore, my invention while especially designated for wedge-shaped justifiers and for my designated machine is broadly applicable to type elements and typographic ma-
 40 chines.

Having fully described my invention, I claim—

1. In a type-magazine, the combination of a receptacle having a channel to receive type elements, a partition, means for moving the partition, and mechanism for regulating the movement.
- 45 2. In a type-magazine, the combination of a receptacle for the type elements, having a movable partition or false bottom, means for

actuating the partition, and an escapement mechanism for regulating the movement.

3. A type-magazine having an upper chan- nnel to receive the type elements, a lower channel with an inclined bottom to discharge 55 the type elements, an intervening movable partition, and means for tilting the type elements, so that they may fall sidewise toward the inclined bottom.

4. A type-magazine for wedge-shaped jus- tifiers having in combination an upper chan- nnel, a lower channel with an inclined bottom, an intervening partition, and means for mov- 60 ing the partition at stated periods, a serrated slide lying in the wall of the upper channel 65 to receive the apexes of the justifiers, and means for reciprocating the slide to tilt the justifiers so that they may fall with their butt- ends directed toward the lower or discharge end of the inclined bottom. 70

5. In a type-magazine, the combination of a receptacle having a channel to receive a se- ries of type elements, a partition or false bot- 75 tom gradually reduced from one end to the other, means for moving the partition to dis- charge the type elements in succession, mech- anism for regulating the movement of the partition, and means for positioning the type elements so that they may be guided in their fall toward the point of discharge. 80

6. In a type-magazine, the combination of a receptacle having a channel to receive and guide a series of type elements, a swinging trapezoidal partition dividing the channel, a rack carrying a spring-pressed trip which en- 85 gages and operates the partition, a pinion op- erated by the rack and carrying a shaft, a spring having a pawl-and-ratchet connection with the shaft so that it is energized by the rotation of the shaft, an escapement mech- anism and intermediate gear connecting it 90 with the spring, and means for operating the rack.

In testimony whereof I affix my signature in presence of two witnesses.

LUCIEN A. BROTT.
